Application July 20, 1956, Serial No. 599,267

Claims priority, application France December 26, 1955

2 Claims. (Cl. 313—105)

This invention relates to electron multiplier and, more particularly, to electrostatic secondary-emission photomultipliers.

Photomultipliers are now employed in a wide variety of applications for converting light energy into signals of useful strength. In an electrostatic photomultiplier, electrons ejected by radiation falling on the photocathode are accelerated toward the first of a series of dynodes at successively higher potentials. These dynodes comprising an electron multiplier have the characteristic of yielding large numbers of secondary emission electrons when bombarded with a relatively few energetic electrons. By cascading the path of secondary electrons through the series of dynodes, a stream of electrons flowing from the last dynode to the photomultiplier anode may be derived of a magnitude proportioned to the numbers of electrons emitted from the photocathode but amplified by a million or more.

In photomultipliers heretofore devised, this performance may be disturbed by a variety of causes, several of which are particularly significant. First, because a perfect vacuum cannot be maintained in photomultipliers over a period of time, residual gases remain which are subject to ionization by collision with accelerated electrons. A positive gaseous ion formed by ionization may be drawn to the photocathode with sufficient energy to eject electrons, thus creating a spurious signal and leading to unstable operation. This disturbance is frequently termed "ion feedback."

A second disturbance arises when the potential gradient at the surface of a dynode becomes so great as to liberate electrons by a process known as "cold emission" or "field emission." This disturbance may arise particularly from non-linearities in potential variation along the electron paths extending between successive dynodes.

A third disturbance arises from the use of an insulating glass envelope to enclose the multiplier structure and of insulators to support parts of this structure. Because of the requirement that successive dynodes be at different potentials, for example, a relatively open space between successive dynodes is frequently provided through which electrons are guided by focusing arrangements. Such focusing never being perfect in practice, some of the electrons traveling between adjacent dynodes escape to the walls of the glass envelope and eject secondary electrons toward the anode. A sufficient positive charge may thus be developed on an insulating surface to result in a "cold emission" discharge and the consequent generation of spurious noise signals at the photomultiplier output terminals. Noise signals may also be derived from so-called microphonics, that is, vibration of the dynode structure in a manner distorting the electron path.

It is an object of the present invention to provide a new and improved photomultiplier in which the above-described disturbances are minimized or eliminated.

More particularly, it is an object of this invention to provide a photomultiplier having an effective arrangement for confining the travel of secondary emission of

2

electrons to a path of substantially uniform potential gradients while shielding against outside perturbations.

Another object of this invention is to provide a photomultiplier of high sensitivity and stability of operation and with a minimum of residual gases.

Yet another object is to provide a photomultiplier requiring a minimum number of signal carrying leads and hence a minimum number of seals between the photomultiplier envelope and such leads.

Still another object is to provide a photomultiplier of simple, rugged construction for ease of assembly and reliability of operation.

These and other objects of the invention are attained by an improved assembly of photomultiplier dynodes arranged not only to yield secondary emission electrons but to focus and confine these electrons while adsorbing positive gaseous ions tending to move toward the photocathode. The assembly comprises spacers enclosing the region between each successive pair of dynodes and having low conductivity interior walls both to linearize the potential variation between successive dynodes and to discharge any particle deviating from the path between successive dynodes.

Each dynode, except the last, comprises strips of electron emissive material presenting an emissive surface to impinging electrons with passages between the strips provided for flow of secondary electrons ejected by such impinging electrons. To focus the impinging electrons on the secondary emissive surfaces, each dynode carries a curved wire mesh arched over the dynode strips to form a convergent, electrostatic lens.

Appropriate portions of these lenses are constructed of a so-called getter material, that is, a material adapted to adsorb the ions of residual gases contained within the photomultiplier.

The invention, together with its objects and advantages will more perfectly be understood from the following detailed description taken in conjunction with the drawings, in which:

Fig. 1 is an elevation of the improved photomultiplier of this invention with portions including the envelope partially cut away to reveal internal features of construction;

Fig. 2 is an exploded view of the first dynode with portions thereof cut away;

Fig. 3 is a sectional view of the photomultiplier of Fig. 1 taken along a diametral plane and illustrating only the lower portion of the photomultiplier, together with a schematic version of circuitry for association therewith; and

Fig. 4 is a schematic view of the photomultiplier to illustrate its circuit equivalent together with representative paths of charged particles.

Throughout the figures like reference numerals are employed to designate similar elements. In accordance with the present invention, a photomultiplier is shown in Fig. 1 comprising an evacuated envelope 10 having therein a photocathode 11, an electron multiplier assembly 12 and an anode 13. The envelope 10 is conveniently of cylindrical configuration and is composed of a material, such as a shock resistant glass, capable of withstanding externally applied pressures and serving as an electrical insulation. At one end of the photomultiplier the envelope 10 provides a window 14 transparent to radiation such as light quanta or photons.

Interiorly of the window 14 are a barrier layer 15 and a photosensitive layer 16 of the photocathode 11. The barrier layer 15 is transparent to the radiations to which the layer 16 is sensitive. Preferably, the layer 15 is deposited on the inner surface of the window 14 and is composed of an electrically conductive substance as described in copending application Serial Number 599,207,

filed July 20, 1956, by J. P. Causse and A. Lallemand for "Photosurface and Method of Making Same." In accordance with this application, the layer 15 further serves chemically to isolate the photosensitive material of layer 16 from constituents, such as boric oxide, which may be contained in window 14.

A conductor 17 connects with the photocathode 11 through a band 18 of silver deposited on the inner wall of the envelope 10 and is led out through the envelope remote from base 19 of the photomultiplier for connection with external circuitry, hereinafter described.

A great variety of known compositions are suitable for the photosensitive layer 16, each having the characteristic of emitting electrons known as photoelectrons upon the incidence of radiation passing through the transparent window 14 and layer 15. For example, the photosensitive layer 16 may be composed of cesium-antimony, sodium-antimony, or any of a variety of intermetallic compounds of alkali or alkaline earth metals and antimony, sulfur, selenium, tellurium, bismuth, thallium, or lead.

To raise the signal represented by the photoelectrons to a useful strength, the electron multiplier assembly 12 comprises a series of dynodes 20a, 20b, . . . 20j and 20k aligned with the photocathode 11 and anode 13, the first dynode 20a being disposed opposite the photocathode 11. As seen in Figs. 1 and 2, the first dynode 20a comprises a centering ring 22a, a plano-convex lens 23a and an axial spacer 24a.

Ring 22a serves to position the dynode 20a along the axis of the envelope 10. To this end, the ring 22a includes a thin, flat annulus 26 of insulating material, such as mica, having a notched circular periphery 27 frictionally engaging the inner wall of the envelope 10, and a circular inner periphery 28 supported in an inwardly crimped portion 29 of an annular axially extending band 30. The band is composed of a conductive material such as aluminum. Below the inwardly crimped portion 29 is provided a downwardly and inwardly directed annular shoulder 31 and above it a flat upwardly directed shoulder 32 for engagement with the lens 23a, as hereinafter described. The upper shoulder 32 formed in the band 30 extends radially outwardly therefrom overlying the insulating annulus 26. The band 30 then provides a conduction path between the outer surface 33 of its axially extending lower portion and the shoulder 32. At the outer periphery 27 of the insulating annulus, uniformly spaced notches may be provided in order that conductor 35, as well as other support rods (not shown) may extend axially along the inner wall of the envelope 10 to the base 19.

The plano-convex lens 23a is, like the centering ring 22a, of a unitary construction and is, moreover, arranged for detachable clamping engagement with the centering ring 22a. The lens comprises a rigid annular frame 37 of generally circular cross section flattened in the axial direction and composed of a conductive material, for example, nickel. Formed snugly about the ring 37 is a channel shaped member 38 opening inwardly and in interior pressure contact with the flattened upper and lower surfaces of the rigid frame 37. Member 38 is also conductive.

Inserted between the upper face of the frame 37 and the channel member 38 are radially extending end portions 39 of fine, arcuate wires 40 lying in spaced axial planes and circularly contoured to define a relatively open, hemispherical mesh having its convex side facing toward the photocathode 11.

Between the lower face of the rigid ring 37 and the inner surface of the channel member 38 pressing thereagainst, tabs 42 formed at either end of dynode strips 43 are inserted to rigidly hold the strips in spaced parallel relation across the aperture defined by the ring 37. The strips 43 are bent out of the horizontal plane of the tabs 42 at an angle, for example, of 45° to the axis of the

lens in order to present their inclined secondary-emissive surfaces 44 to the photoelectrons from the photocathode 11 for impingement at an angle. For good secondary emission characteristics, the upper surface 44 of the strips 43 is, for example, composed of a silver-magnesium alloy. By reason of this inclined strip construction, the dynode 20a may be referred to as a "Venetian blind" type.

To minimize ion feedback to the photocathode 11, both the mesh wires 40 and the undersurfaces of the dynode strips 43 are composed of a metal having the qualities of a getter, that is, the property of discharging and absorbing gaseous molecules formed when a positively charged gaseous ion impinges. Satisfactory getter materials include titanium, molybdenum, zirconium, tantalum, palladium, and others.

To the underface 46 of the channel member 38 is secured a wire ring 47 sized for snugly fitting within the inwardly crimped portion 29 of the centering ring 22 when the underface 46 is resting on the shoulder 32. Also attached to the underface 46 are a plurality of spring fingers 48 extending downwardly in a generally tangential relation to the annular channel member 38. When the lens 23a is assembled with the centering ring 22a, the spring fingers 48 will extend under the inwardly crimped portion 29 of the centering ring and bear resiliently against the inclined shoulder 31 to cam the centering ring 22a and lens 23a into firm contact. A good electrical connection is thereby effected, so that the entire lens 23a and the band portion 30 of the centering ring 22a may be at the same electrical potential.

The remaining component of the dynode unit 20a, namely, the axial spacer 24a, has the form of a cylindrical band with an interior diameter sized to snugly receive the band portion 30 of the centering ring 22a. When thus frictionally interfitted with the centering ring 22a, the spacer 24a has its upper surface 49 bearing against the insulating annulus 26. As seen in Fig. 1, the spacer 24a also snugly receives lens 23b of the second dynode unit 20b. The bottom edge 50 of the spacer is then held against the upwardly facing shoulder 32 of the centering ring for the second dynode unit 20b.

In order that the potential gradient between successive dynodes may be rendered more uniform, the spacer 24a has a composition which affords a low conductivity path. Since the electrostatic field lies within the spacer and since the inner surface of the spacer makes pressure contact both with the centering band 30 and the lens channel member 38, it is only necessary that the inner surface exhibit conductivity. Hence, the spacer may be composed of an insulating material such as glass, a ceramic or the like, preferably with its inner surface having a layer 51 of conductive material deposited on it. The layers may, for example, be composed of gold or silver evaporated upon the inner surface or, if desired, a getter material of appreciable conductivity. Moreover, the bulk of the spacer 24 may itself be somewhat conductive. While the required conductivity of the spacer 24 will depend upon the current drawn from the dynodes and the potential difference existing between adjacent dynodes, its resistance may be on the order of 200 kilohms with about 150 to 200 volts between successive dynodes. Preferably, the resistance will have a low temperature coefficient, especially where the photomultiplier may be employed in variable high temperature environments such as are encountered in radioactivity well logging.

While the foregoing description has been particularly directed to the dynode unit 20a, it will apply with equal force to the dynode units 20b through 20i. A difference will be observed, however, in the later dynodes of the series as their spacers are shorter in axial length and the wire mesh of the lenses becomes shallower, that is, of a larger radius of curvature. Moreover, the spacer 24j is provided with an aperture 52.

The anode 13, preferably formed of a wire grid as seen in Fig. 1, is disposed within a conductive cylinder 53,

known as a "Faraday box," having an aperture 54. A lead-in wire 55 passing through a seal 56 in the base 19 and through the apertures 52 and 54 supports the anode 13 firmly. The cylinder 53 may be secured to the dynode 20k conductively.

For efficient production of secondary emission electrons from the last dynode 20k, this dynode is formed as a circular plate closely underlying the grid-like anode 13. The periphery of the dynode 20k is sized to fit within the bottom end of the cylinder 52 and is in electrical contact with the inner conductive getter layer 51 of the same. A conductive lead 57 passing through a seal 58 in the base 19 affords electrical contact with the dynode 20k and, at the same time, rigidly supports the same and the cylinder 52 in spaced relation to the dynode 20j.

The rugged mounting of the electron multiplier structure may be observed then to follow from the snug contact between the insulating annuli 26 and the inner wall of the envelope 10, the snug interfitting of the lens, centering ring, and spacer for the successive dynode units, and the rigid supports afforded by the leads 35, 55 and 57 passing, respectively, out of the base 19 through seals 36, 56 and 58. The linear arrangement of the Venetian blind dynodes, furthermore, facilitates ready manufacture of the dynode units such that snug interfitting may be obtained with economy.

If desired, additional lead-in conductors (not shown) may be connected to each of the dynodes 20b, . . . 20j in the same manner that conductor 35 connects with dynode 20a further to rigidify the assembly. As will be more fully described hereafter, however, these additional conductors are unnecessary to the establishment of suitable potentials on the dynodes in view of the employment of the conductive spacers interconnecting the successive dynodes, but may nonetheless be employed for this purpose, if desired.

In Fig. 3 suitable means for energizing the photomultiplier is shown comprising a D.C. source 60 connected across a potentiometer 61 having its negative terminal connected to conductor 17 and its positive terminal connected through resistor 59 to the anode 13. Connected to a tap 62 in the potentiometer close to its positive terminal is conductor 57, whereby the potential on the last dynode 20k is made less positive than the anode 13. Coupling means such as capacitor 63 connected to the anode 13 serves to couple the signal developed across the resistor 59 to an indicating circuit or the like (not shown). Conductor 35 connects the first dynode 20a with a tap 65 toward the negative end of the potentiometer 61. In this manner, the potential between the first dynode 20a and the photocathode 11 may be fixed at a suitable value governing acceleration of photoelectrons emanating from the photocathode. If desired, additional conductors, similar to conductor 35, might be arranged for connecting each of the dynodes 20b, . . . 20j appropriately to the potentiometer 61 but such additional connections would be largely superfluous in view of the conductive character of the spacers.

In Fig. 4, the spacers 24a, . . . 24i are schematically represented as resistors connecting between the corresponding pairs of dynodes 20a, 20b, . . . 20j and 20k. This representation illustrates more clearly the significance of the spacers in establishing successively higher potentials proceeding from the photocathode 11 through the first, thence to the last dynode and finally to the anode 13. Because the inner walls of the spacers are conductive, moreover, they tend to render substantially uniform the potential gradient in an axial direction along the walls. The effect of the spacers in conjunction with the plano-convex lenses forming the series of dynodes is exemplified by the representations of cascaded electron paths 67 stemming from a single photoelectron 68 emitted from the cathode 11. Also exemplified are representative paths 69 for positive ions 70 formed as collision products of the accelerated secondary emission electrons. These posi-

tive ions, indicated in Fig. 4 by a positive sign, are shown impinging in one instance upon a wire 40 of the spherical mesh for dynode 20e and, in the other instance, impinging upon the undersurface of a dynode strip 43 of the second dynode 20b. It will be appreciated, of course, that only a fragment of the actual electron paths may be represented and that the high gain per stage precludes an intelligible representation of paths through the entire series of dynodes.

In operation, a D.C. potential source 60 is energized to apply a positive D.C. potential on the anode 13, a less positive potential on the dynode 20k, and a negative potential on the photocathode 11. A somewhat less negative potential may also be applied to the first dynode 20a. Whenever photons or other radiant energy impinge upon the photocathode 11, photoelectrons are ejected and are drawn from the region of the cathode toward the higher potential field of the first dynode. As the photoelectrons approach the convex side of the wire mesh 40, all of them converge inwardly toward the axis of the photo-tube and of the first lens. This results from the convergence of the electric field between lenses produced by the mesh curvature. Hence, the photoelectrons are electrostatically attracted toward the axis, thereby increasing the collection efficiency of the first dynode and preventing photoelectrons from straying to the wall.

Most of the photoelectrons will impinge upon the secondary emissive surfaces of strips 43 to eject secondary electrons therefrom. Since the secondary electrons may number in the ratio of 4 to 1, on the average, relative to the numbers of incident photoelectrons, electrons representing the difference between the captured and the emitted electrons will flow from the source 60 through the conductor 35 to the dynode 20a. At the same time, the secondary electrons will be drawn convergently toward the second dynode 20b, repeating the secondary emission process, and the process will thus cascade through the series of dynodes. Finally, some of the secondary electrons emitted by the dynode 20j will pass directly to the anode 13 while perhaps the greater number will pass through the anode 13 striking the last dynode 20k to produce yet additional secondary electrons. Substantially all of the secondary electrons eventually result in an electron flow to the anode 13 yielding a current there-through substantially linearly proportioned to the intensity of light incident upon the photocathode 11. The withdrawal of electrons by the secondary emission process tends to drive each dynode positively, so that electrons flow from the source through conductor 35 and the spacers to the dynodes to restore each to its normal potential.

In the event that electrons strike the inner walls of the spacers despite the convergent fields established by the lenses, the conductivity of the spacers will allow such electrons to be discharged through the last dynode 20k to the power supply tap 62. Because the conductivity of the spacers is sufficiently large to permit an appreciable current to pass from the last dynode to the first dynode, however, the very slight current produced by electron collisions with the inner walls of the spacers will have no significant effect upon the proper operation of the photomultiplier.

Within the lenses, the electrons will generally exhibit their highest velocities due to the accelerating potential on the mesh and the dynode strips. Accordingly, ionization of residual gas molecules remaining after evacuation of the photomultiplier may occur particularly in these regions within the lenses. In order to prevent travel of positive gaseous ions thus produced back to the photocathode 11, the surfaces which such positive ions likely might strike are prepared for capturing or adsorbing the ions at the same time neutralizing their charge. Thus, positive ions may impinge upon the undersurfaces 45 of the dynode strips or upon the wires 40 of the spherical meshes, each of which are composed of getter material.

In this manner, regenerative ion feedback and consequent instabilities are avoided. It may be noted that the spherical wire mesh of each dynode, being at the potential of the corresponding secondary emission surface, enhances both the yield and the collection of secondary emission electrons.

In the event that the photomultiplier is subject to shock or vibrational forces applied to the envelope, these forces will be transmitted through the centering rings 22a, . . . 22j to the firmly connected lenses and spacers so that the entire assemblage will have a unitary motion.

As seen particularly in Fig. 4, the lens structure will produce a higher potential gradient along the axis of the phototube, but for a shorter distance, than the potential gradients in the axial direction displaced radially from the axis of the tube. Where the expression is used that the spacers tend to render the potential gradient more uniform, this should be understood as meaning that the potential gradient experienced by electrons traversing an axial path between successive lenses or dynodes will experience substantially a constant potential gradient, although the gradients along adjacent paths may be either greater or smaller.

While a preferred embodiment of the invention has been shown and described, it will be evident that various modifications may be made without departure from the principles of the invention. Thus, in lieu of a photocathode formed on the interior face of the window 14, a photocathode might be disposed in front of the first dynode at the focus of a Schmidt type optical system coupled to the source of radiation. The spherical wire mesh defining the convex surface of the electrostatic lenses might be formed of wires woven in a criss-cross pattern. In lieu of constructing each of the dynodes with getter material at the undersurface of the wires 40 and at the undersurfaces 45 of the dynode strips, only the latter five or so of the dynodes might be so constructed, these being in the region where ionization is most apt to occur.

If desired, a coating of low conductivity similar to the coating 51 might be applied along the inner side walls of the cylinder 53 further to reduce the occurrence of ion feedback within the tube. By the use of appropriate circuitry, the phototube may be energized from an alternating current source in lieu of the D.-C. source 60. Of course, fewer or more dynodes may be employed, as desired.

As the above-described embodiments of the invention are illustrative and are subject to further modifications which may occur to those skilled in the art, the invention is not to be limited except as defined in the appended claims.

I claim:

1. In an electron multiplier, a cathode, an anode, a plurality of dynodes, each dynode including a circular frame, strips secured by said frame in spaced apart relation inclined with respect to the axis of said frame and having secondary emissive surfaces confronting said cathode, a wire mesh lens arched over said surfaces and secured to said frame, said strips having their surfaces which confront said anode composed of an adsorptive gettering material, a plurality of insulating cylindrical spacers stacked in endwise alignment, a plurality of centering rings extending between the endwise surfaces of adjacent spacers and conductively secured to corresponding ones of said frames to support said dynodes in spaced axial alignment within the stack of said spacers intermediate said cathode and anode, envelope means supported in axial alignment with said stack of spacers by at least two of said centering rings for enclosing said cathode and anode in sealed relation with said dynodes, a pair of leads extending in sealed relation through said envelope means for applying a potential difference between said cathode and anode, and high-valued resistances extending along said stack of spacers and in electrical contact with said centering rings to provide a potential divider between said dynodes.

2. An electron multiplier, as defined in claim 1, wherein in said centering rings are secured in full annular supporting contact with respect to said dynode frames interiorly of said stack of spacers, each of said centering rings being secured in full annular supporting contact with respect to an adjacent one of said spacers.
